SIGNAL STORAGE TUBE

Joachim E. Otto, Ulm (Danube), Germany, assignor to
Telefunken G.m.b.H., Berlin, Germany

Application March 30, 1959, Serial No. 802,770

Claims priority, application Germany April 3, 1958

15 Claims. (Cl. 315—12)

The present invention relates to storing of electrical signals and, more particularly, to a signal storage tube having a substantially strip-shaped target electrode and one or two electron guns used for producing both writing and reading beams.

In the following discussion, each type of signal storing cathode ray tube is briefly called a "storage tube," while each kind of signal storing electrode is called a "target electrode."

The necessity of storing electrical signals for a limited period of time arises, for example, if the video frequency signal band in a radar set has first to be compressed prior to its transmission, for the purpose of transmission by means having a band width which is narrower than said signal band. Signal storage tubes are particularly suitable for this purpose.

In storage tubes for this and other similar purposes, wherein signals are recorded on target electrodes, it is usual practice to cause an electron beam which has been intensity-modulated by the signal voltage to travel once or several times over said target electrode using suitable deflection means, whereby changes in the electrical charges on said target electrode are stored, said changes being dependent on the instantaneous intensities of the respective beam-modulating signals. The methods of producing such changes are well known. With known storage tubes, the intensity modulation of the electron beam is obtained by means of cathode control or Wehnelt electrode control.

In said storage tubes, both the pick-up and the obliteration of the stored signals are likewise obtained by means of an electron beam which, however, has a constant intensity and which is caused to travel with the aid of deflecting means at suitable velocity once over the same track on the target electrode along which the first electron beam travelled when writing the respective signals, whereby signal voltage variations are obtained in a working resistance inserted in the circuit of a signal collecting plate on the side of the target electrode facing away from the electron gun. In their amplitude distribution, the above-mentioned voltage variations follow the stored charge distribution on the track of the target electrode and, in this way, they represent the signals stored thereon.

When using the above type of storage tube, there appears the disadvantage that, due to the nonlinearity of the beam current characteristic of the Wehnelt electrode potential, the relationship between the control voltage and the beam current is also nonlinear, whereby the amplitude of the signals to be transmitted is distorted. In addition, it is often necessary in the operation of such storage tubes that a direct-current component be superimposed to the alternating-current component of the beam current including the signal. Due to the non-linear shape of the curve characteristic, an optimum adjustment of the operating characteristic of the storage tube is not readily possible in case of high amplitude signals.

Moreover, the output signal with compressed band-

2

width in this type of storage tube also contains, even in the absence of input signals, the compressed noise spectrum of all of the preceding stages of the apparatus. Furthermore, it should be borne in mind that the range of information which can be stored is rather small.

With other embodiments of storage tubes which are suitable for the above-mentioned purpose, the changes in either the electrical charges or in the electrical properties of the target electrode are obtained by applying the signal voltage to a collector electrode or to a grid-like electrode, disposed immediately before or directly on the target electrode, or by applying said signal voltage to the target electrode itself in cooperation with an electron beam of constant intensity which is caused to travel once or several times over said target electrode by suitable deflecting means. The methods causing said changes in the target electrode of such tubes are likewise known per se. With said storage tubes, the pick-up and, if required, also the obliteration of the stored signals are done by means of an electron beam having a constant intensity, which electron beam is also swept by deflecting means once at a suitable velocity over the same track on the target electrode over which the first electron beam was swept when writing the respective signals. The resulting voltage variations appear across a working resistance inserted in the circuit of a signal electrode which is provided either on the side of the target electrode facing away from the electron emitting source, or which is designed as a grid and is provided adjacent the side facing said electron emitting source. In their amplitude distribution, said voltage variations represent the signals stored on the track of the target electrode.

Using this type of storage tube, it has, likewise, been found disadvantageous that the output signal of compressed band width, even in the absence of input signals, always contains the compressed noise spectrum of the preceding stages. In addition, it should be taken into consideration that the range of information is also small.

Embodiments of the two aforementioned groups of storage tubes have been known, in which the electron beam or beams have a circular or rectangular cross section. Furthermore, cathode ray tubes have been known having an electron beam of circular cross section. In these tubes, the electron beam is subjected to a deflection which is dependent on the amplitude of the signal voltage fed to the tube, as in oscilloscope tubes.

It is an object of the present invention to provide a storage tube in which the aforementioned disadvantages are overcome by a suitable design of the electron beam and by means of a different control system. In the following, the deflection of the electron beam, dependent on the signal voltage, will be explained as being distinguished from the cyclical electron beam sweep.

It is another object of the invention to provide a storage tube in which the electron beam is designed as a band-shaped electron beam having a cross-sectional ratio of at least 1:5, so that the longer cross-sectional dimensions of the electron beams are oriented perpendicularly to the longitudinal extension of the target electrode over which the electron beams travel. Means are provided by which the writing beam, depending on the signal to be stored, is deflected in the direction of the longer cross-sectional dimension of the electron beam; and the band-shaped beams have a constant mean intensity for one deflecting operation whether a writing cycle or reading cycle.

Still further objects and the entire scope of applicability of the present invention will become apparent from the detailed description given hereinafter; it should be understood, however, that the detailed description and

specific examples, while indicating preferred embodiments of the invention, are given by way of illustration only, since various changes and modifications within the spirit and scope of the invention will become apparent to those skilled in the art from this detailed description.

In the drawings:

Figure 1 is a fragmentary schematic showing of a band-shaped beam impinging on a target electrode, and

Figure 2 is a partial perspective view showing a storage tube electrode arrangement according to the invention.

Referring in detail to the drawings, Figure 1 schematically shows a portion of an elongated target electrode on which two tracks 3 and 4 adjacent one another are provided side by side and a signal collecting plate 5 is arranged on the side of the target electrode opposite the electron-emitting source, in the circuit of which a load resistance 6 is inserted. Also forming a part of the circuit is an electron beam 1 having an approximately rectangular cross section, said beam being caused to travel over said target electrode in the direction of the arrow by sweep means (not shown). The signal is applied across a pair of beam deflection electrodes 2 to modulate the position of the beam on the target. To avoid crowding of the drawing, the conventional collector electrode is omitted. As long as no signal voltage is applied to the deflecting plates 2, the electron beam 1 will travel along the track 3, but when a signal voltage is applied to the deflecting plates 2, the electron beam 1, while being swept over the target electrode in the direction of the arrow, will be deflected from the track 3 to the track 4, whereby the relative electrical state of charge of the two tracks 3 and 4 of the target electrode will be changed, said state of charge being indicated by shading in Figure 1.

For pick-up of the signals stored in the target electrode, there is used also an electron beam 1 having an approximately rectangular cross section, said beam being produced either by means of the same electron gun used for the signal writing electron beam, or by means of another electron gun, whereby said second beam (not shown) is swept over the target electrode at a suitable velocity by conventional deflecting means. The longer cross-sectional dimension of the electron beam picking up the stored signals should be designed such, that it extends from the inner edge to at least the outer edge over the entire width of one track.

Figure 1 shows an arrangement having two similar tracks. If, with said arrangement, the electron pick-up beam is caused to travel along the track 3, the stored signal will be represented by the gaps on said track, whereas, if the electron pick-up beam is swept along the track 4, the stored signals will be represented on said latter track by the spots charged by the deflected signal-writing electron beam. With the use of either of the two aforementioned systems, pick-up voltage variations will appear in the load resistance 6, said variations corresponding to the stored signals, whereby the polarities of the voltage variations in the load resistance, however, are opposite in the two possibly different pick-up tracks. The two tracks 3 and 4 may be designed to be either similar to or different from one another.

Obviously, the track on the target electrode, from which no stored signals are to be taken up, need not have any storing action which means that it may be, for instance, a collector electrode.

Furthermore, it is evident that the track designed to be a collector electrode need not be in the plane of the track comprising the target electrode. On the contrary, the track designed to be a collector electrode may be arranged so that it is shifted from the plane of the target track in the direction of the electron emitting source as well as in the other direction.

In case of similar design of the two tracks, it will be advantageous for various purposes, if either track has its own signal collector plate electrically insulated from the signal plate of the other track, whereby a load resistance

can be inserted in the circuit of either signal plate. If, with the use of the abovementioned target electrode, the stored signals are picked up from the two tracks by means of an electron beam having a band-like cross section, the longer cross-sectional axis of which reaches at least over the entire width of the two tracks, two para-phased output signal voltages will be available at the two load resistances.

In the above mentioned embodiments of target electrodes employed in the storage tube designed in accordance with this invention, the two tracks may be arranged with their long sides adjacent one another and spaced at a suitable distance, for the purpose of fully suppressing the noise level in the input signal of the storage tube or for 10 the purpose of obtaining a threshold value.

It is evident that the above described embodiments of the storage tube according to this invention are not confined to arrangements with linear tracks, i.e., the tracks may also be circular.

Figure 2 schematically shows the essential components of the embodiment of a signal storage tube having an annular target electrode, the structure of which is principally the same as that of the target electrode shown in Figure 1. The means for obtaining a strip-like beam 20 will be explained with reference to Figure 2.

An electron beam having a circular cross section is first produced by means of both a cathode 11 and a symmetrically designed Wehnelt cylinder 12, said electron beam being adapted to be focussed onto the tracks 30 of the target electrode by means of symmetrically designed electrodes 13, 14, 15, representing an electron lens. The electron lens 13, 14, 15, has been designed as an electrostatic single lens. This electron lens may also be designed as an electrostatic accelerator lens or 35 a magnetic lens. In the embodiment of Figure 2, the electron beam is circularly swept by means of a pair of deflecting coils (not shown), although electrostatic deflecting means may be employed. The swept electron beam, having a circular cross section, is spread in a direction radial with respect to the axis of the electron gun 40 by means of the annular electrostatic cylinder lens 16, 17, 18, which produces an annular cylindrical field, so that that the electron beam 10, when impinging on the target electrode 24, has an approximately rectangular cross section. In the embodiment of Figure 2, the annular cylinder is designed as an electrostatic single lens. An annular electrostatic accelerator lens may, likewise, be used, said lens producing an annular cylindrical field. The electron beam, which is spread apart by annular deflection means comprising two rings 19 and 20, is also 45 radially deflected in accordance with the signal to be stored. The target electrode may be designed as shown in Figure 1, i.e., it may have two side-by-side annular tracks. Reference numbers 22 and 23 are interconnected collector electrodes. On the back side of the target electrode, there is provided a metallic annular signal plate 25 which is returned to ground potential via a resistance 26. When the reading beam sweeps over the target electrode, the signal voltage regained from storage will cause a 50 voltage drop across the resistance 26. Obviously, the various design possibilities for the target electrode, as shown in Figure 1, may, likewise, be applied to the annular target electrode illustrated in Figure 2.

The storage tube according to this invention has the 55 advantages of linear relationship between the amplitudes of the input signal voltage and those of the output signal voltage since, as has been known per se, electrostatic deflection is linear. Moreover, the range of intelligence which can be stored may be of almost any magnitude, due 60 to the scanning principle according to this invention. Since the mean intensities of both the writing beam and the reading beam are kept constant, the working point on the characteristic curve which is most favorable for the deflection can always be adjusted independently of the input signal. Last, but not least, the system accord-

ing to this invention has the advantage that both the writing beam and the reading beam can also be intensity modulated by other signals.

I claim:

1. A signal storage tube having an elongated target electrode and having at least one electron gun for producing reading and writing beams and having sweep means for sweeping the target with the beams, characterized in that the electron beams have band-like cross-sectional shapes with the longer transverse beam dimension disposed transversely of the longitudinal dimension of the target electrode over which said electron beams are swept; beam deflection means acting on the writing beam for deflecting the latter transversely of the target electrode in response to signals to be stored thereon so as to position-modulate the writing beam, and said beams having a constant mean intensity over each swept cycle.

2. A signal storage tube, as set forth in claim 1, characterized in that the target electrode comprises two parallel tracks the width of which at least equals the longer cross-sectional dimension of an electron beam, the electron beam sweeping along one track when undeflected and being displaced at least partially onto the other track when deflected.

3. A signal storage tube as set forth in claim 2, characterized in that one track comprises a collector electrode, while the other track comprises a storage electrode.

4. A signal storage tube as set forth in claim 2, characterized in that the two tracks comprise electrically mutually insulated storage electrodes.

5. A signal storage tube as set forth in claim 3, characterized in that the two tracks have been arranged closely parallel to one another and mutually electrically insulated from each other.

6. A signal storage tube as set forth in claim 3, characterized in that the two tracks have been arranged at a small distance from one another and electrically insulated from each other.

7. A signal storage tube as set forth in claim 2, characterized in that the target electrode has a single storing layer comprising both tracks.

8. A signal storage tube as set forth in claim 1, charac-

terized in that the intensity of the beam used for the writing cycle is different from the intensity of the beam used for the reading cycle.

9. A signal storage tube as set forth in claim 1, characterized in that the beam cross section during the reading cycle extends transversely of the target electrode at least twice the width of one track.

10. A signal storage tube as set forth in claim 1, characterized in that the target electrode is annular and normal to the axis of the gun.

11. A signal storage tube as set forth in claim 10, characterized by beam-shaping means between the sweep means and the target electrode for distorting the beam emitted by the electron gun from a beam of circular cross section into an elongated beam, the longer dimension of which is radial as applied to the annular target electrode; and said beam deflection means comprising annular deflecting electrodes for deflecting the beam in said radial direction.

20 12. A signal storage tube as set forth in claim 11, characterized in that the beam-shaping means comprises an annular cylinder lens.

13. A signal storage tube as set forth in claim 11, characterized in that said deflection means comprises annular concentric deflection plates.

14. A signal storage tube as set forth in claim 13, characterized in that said deflection plates comprise several separate sections for the purpose of improving the sensitivity of deflection.

30 15. A signal storage tube as set forth in claim 11, characterized in that the deflection means comprise several pairs of concentric truncated surfaces of revolution disposed in spaced relation along the tube, the directly concentrically adjacent parts of which are applied to the same potential; and that the parting lines between the pairs have been designed such, that the beam will be subject to deflection if there are different voltages on said spaced pairs.
